OIL BURNER AND FUEL CUTOFF SYSTEM

Howard E. Earl, Bloomington, Ill., assignor to
 Eureka Williams Corporation, Bloomington,
 Ill., a corporation of Michigan

Application January 17, 1948, Serial No. 2,881

17 Claims. (Cl. 158—42.1)

1

This invention relates to oil burner systems and has particular relation to low pressure oil burner systems in which a combustible charge is formed by mixing together a small quantity of air and fuel at substantially equal low pressures and then igniting and burning this mixture beyond a burner nozzle through which the main air supply for the burner system also is discharged.

Some of the objects of the invention are to provide:

An oil burner system of the low pressure type in which the oil supply to the mixing nozzle remains automatically cut off until the mechanical elements of the system are operating at a predetermined or normal operating speed and then supplying fuel to the nozzle during the normal operation of the burner.

An oil burner system in which the oil supply to the mixing nozzle of the burner is cut off when the mechanical elements of the burner cease to operate under normal operating conditions and start to slow down at the end of a burner operating cycle.

An oil burner employing a pumping unit as one of the mechanical elements thereof and in which pumping unit the oil pumping mechanism is rendered inoperative below a predetermined or normal operating speed for such mechanism.

An oil burner system employing a centrifugally actuated switch, a solenoid actuated valve, and a fuel pumping mechanism, all of which operate in such manner as to cut off the fuel supply to the burner nozzle at the beginning and at the end of an operational cycle when the mechanical elements of the burner system are operating below a predetermined operating speed.

Other and further objects of the invention will be apparent by reference to the accompanying drawings of which there are two sheets, which by way of illustration, show a preferred embodiment and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims. I also contemplate that of the several different features of my invention, certain ones thereof may be advantageously employed in some applications separate and apart from the remainder of the features.

Referring particularly to the drawings:

Fig. 1 illustrates an elevational view of an oil burner system embracing the principles of the invention.

Figs. 2 and 3 represent a schematic view of the

2

principal elements of the charge forming and fuel burning elements of the oil burner system illustrated by Fig. 1.

Fig. 4 is a fragmentary transverse sectional view through the fuel metering pump embraced in the fuel pumping mechanism illustrated by Fig. 2. Fig. 4 is taken in the plane of line 4—4 on Fig. 2 looking in the direction of the arrows.

Referring particularly to Fig. 1, the numeral 10 indicates generally an oil burner apparatus or system adapted to be supported upon a frame 11. Extending upwardly from the central portion of the frame 11 is a housing 12 to which is attached on opposite sides of the top thereof a motor 13 and a pumping unit 14. The central portion of the aforesaid upper part of the housing 12 provides a fan housing 15 in which is located a centrifugal fan or blower 17. The motor 13 drives the fan 17 through a driving shaft 18 and which shaft in turn drives the shaft 19 of the pumping unit 14 through a coupling 21. A transformer 22 for the electrical apparatus of the system is secured to one side of the lower part of the housing 12, while the oil burner control mechanism 23 is secured to the opposite side of the lower portion of the housing 12.

The main air supply for the oil burner system 10 is supplied by the fan 17 through a main air supply conduit 24 which terminates in a secondary burner nozzle 26 adapted to be disposed in the fire box or combustion chamber of a heating system, not shown, but with which the oil burner apparatus referred to is adapted to be employed. Burner nozzle 26 is provided with spirally disposed internally projecting vanes 27 for rotating or whirling the main air supply received from the conduit 24. Immediately within the end of the burner nozzle 26 is a low pressure air and oil mixing nozzle 28 which is adapted to supply a rich mixture of oil and air to the central portion of the burner nozzle 26 to be ignited and burned with the main air supply received from the conduit 24. The mixing nozzle 28 comprises a discharge orifice 29 communicating with a plurality of mixing passages 31 which in turn communicate with an annular air supply passage 32 formed internally of the mixing nozzle 28. Within the air supply passage 32 is formed a fuel supply chamber 33 which communicates with the mixing passages 31 through angularly disposed fuel supply passages 34. Extending coaxially with respect to the air supply conduit 24 is a pair of air and fuel delivery conduits 36 and 37 respectively within which are provided air and fuel delivering passages 38 and 39, also respectively. The passage 38 communicates with the air supply chamber 32, while the passage 39 communicates with the fuel supply chamber 33.

Supported upon the air delivery conduit 36 just back of the mixing nozzle 28 is an adjustable bracket 41 in which an ignitor 42 for the oil burner apparatus is secured. The ignitor 42 is provided with electrodes 44 adjacent the discharge orifice 29 and within the burner nozzle 26. The electrodes 44 are adapted to provide an electrical spark at the beginning of each cycle of operations of the oil burner apparatus for igniting the combustible mixture formed within the burner nozzle 26 by the fuel and air mixture discharged by the orifice 29 and the main air supply delivered to the burner nozzle by the conduit 24.

The pumping unit 14 comprises a casing 16 within which is contained an air supply pump 46, a fuel supply pump 47, and a fuel metering pump 48. The pumps 46, 47, and 48 are all mounted within the casing 16 in such manner as to be driven by the pumping unit shaft 19. The air pump 46 is formed in an air pump housing 49 secured to one side of a central web or support portion 51 of the casing 16, while the fuel pump 47 and fuel metering pump 48 are disposed within a housing 52 secured to the opposite side of the support 51. The shaft 19 is mounted within the pump housings 49 and 52 upon self-aligning bearings 53 and 54, and between the bearings there is provided a fluid seal 56 having a movable member 57 secured to the shaft 19 and a stationary member 58 secured by a diaphragm 59 to one side of the support 51. The support 51 and the pump housing 52 are provided with a centrally disposed fuel chamber 61 in which the seal 56 and the bearing 54 are located.

The air pump 46 is provided with an inlet port 62 communicating with an inlet passage 63 which supplies air to the pump 46 from the annular space within the casing 16 surrounding the housings 49 and 52. A discharge port 64 is provided in the housing 49 on the discharge side of the pump 46. The discharge port 64 communicates with the discharge passage 66 which communicates with the air delivery passage 33 for supplying air to the nozzle 28 through an air supply conduit 67. The passage 66 is also provided with a by-pass 68 controlled by a needle valve 69 which is accessible from the exterior of the casing 16. The opposite end of the by-pass 68 is in open communication with the annular space within the casing 16 through a port indicated at 70.

The fuel pump 47 has an inlet port 71 communicating with an inlet passage 72 supplied with fuel from a fuel supply chamber 73 which in turn communicates with the fuel supply tank, not shown, through a conduit 74. The fuel discharge for the pump 47 is provided by a discharge port 76 which communicates with the chamber 61 through a discharge passage 77. A by-pass 78 from the chamber 61 permits fuel to return to the fuel tank through a by-pass valve 79 and a fuel return conduit 81, also communicating with the tank not shown.

Instead of employing the conduit 81, the opening in the casing 16 in which the conduit is threaded may be closed by a plug and in such event the by-pass 78 may communicate with the fuel supply chamber 73 through an opening, not shown, but which may be formed axially with respect to a screw 82 disposed in a threaded opening 83 formed in the casing 16 in such manner as to communicate with the by-pass 78. The chamber 61 also communicates through delivery passages 86 with a pumping chamber 87 formed

in the housing 52. The fuel metering pump 48 is located within the pumping chamber 87.

In order to provide a resilient drive means for the fuel metering pump 48, the shaft coupling 21, the bearings 53 and 54, and the pumps 46 and 47 are all mounted upon the shaft 19 in such manner as to permit axial movement of the shaft 19 within the bearings 53 and 54. In order to provide means for resiliently urging the shaft 19 within the bearings 53 and 54 in a direction toward the fuel metering pump 48, there is provided within the chamber 61 and beyond the diaphragm 56 a spring 88 which is disposed between the pumping housing 49 and the stationary member 58 of the seal 56. The spring 88, being under compression, tends therefore to move the shaft 19 toward the fuel metering pump 48 by reason of the fact that the seal 56 is secured to the shaft 19 by the rotating member 57 of the seal 56. The end of the shaft 19 terminates at the pumping chamber 87 adjacent the rotor 89 of the metering pump 48 which is adapted to be rotated by the shaft 19 against a wall indicated at 91 formed in the housing 52 on one side of the pumping chamber 87. The rotor 89 is rotated by the shaft 19 through the energy imparted by a ball 92 which is partly seated in openings 93 and 94 formed in the shaft 19 and rotor 89 respectively. The opening 93 is formed in the end of the shaft 19 eccentrically with respect thereto, while the opening 94 is formed in the rotor 89 concentrically with respect thereto. It will be apparent that the spring 88 tends to hold the shaft 19 resiliently against the ball 92 and that the ball 92 tends to hold the rotor 89 resiliently against the wall 91. The rotor 89 has a radially disposed cylindrical opening 96 formed therein in which is reciprocably mounted a piston 97. The opposite end of the piston 97 is resiliently mounted upon a spring 98 in a spherical bearing member 99 which is mounted for linear and oscillatory movement in a cylindrical opening 101 formed in the housing 52 in parallel relation to the axis of the shaft 19. The cylindrical opening 101 communicates with and provides a continuation of the pumping chamber 87.

The wall 91 is provided with an annular pressure chamber 102 which is formed as a groove 103 extending within the wall and against which groove the rotor 89 rotates. The chamber 102 communicates through a passage 104 with a discharge port 104 which is also formed in the wall 91 and which communicates with the cylinder 96 through a passage 106 when the piston 97 is moving inwardly with respect to the cylinder 96. The passage 106 is formed in the rotor 89 between the cylinder 96 and the wall 91. An inlet port 107 also is formed in the wall 91 and within the annular pressure chamber 102 and is adapted to communicate with the passage 106 when the piston 97 is moving outwardly within the cylinder 96. The inlet port 107 communicates with the pressure chamber 87 through an inlet passage 108 while the discharge port 104 communicates with the fuel delivery passage 89 through a fuel supply passage 109 and a fuel supply conduit 111. The passages 108 and 109 are respectively connected to surge chambers 112 and 113 which are adapted to dampen out vibrations in fluid pressure which may occur within the passages.

The fuel supply conduit 111 is connected intermediate the ends thereof to a valve casing 114 having an orifice 116 controlled by a needle valve

117 operated by the armature 118 of a solenoid 119 of a solenoid actuated valve member 121.

When the solenoid 119 is electrically energized the armature 118 will be moved in such manner as to open the needle valve 117 with respect to the seat 116 to permit the normal flow of fluid through the fuel supply conduit 111. When the solenoid 119 is not energized the needle valve 117 will close by gravity upon its seat 116 thereby preventing the flow of fuel through the fuel supply conduit 111. Mounted upon shaft 18 of the motor 13 is a centrifugally actuated switch 122 having a contact member 123 adapted alternately to close an electrical circuit through the starting winding 124 of the motor 13 and the solenoid 119 of the solenoid actuated valve 121. The contact member 123 has a two-way contact 126 adapted alternately to engage contacts 127 and 128 for such respective purposes. The contact member 123 is mounted at the end thereof opposite the contacts 126 upon a portion of the motor frame 129 through which the shaft 18 projects. On one side of the contact member 123 is a projection indicated at 131 adapted to be engaged by a collar 132 surrounding the shaft 18 and which collar is adapted to be resiliently urged toward the contact member 123 by a spring 133 also disposed about the shaft 18. The opposite end of the spring 133 abuts a bracket 134 mounted rigidly upon and adapted to rotate with the shaft 18. The bracket 134 has arms 135 projecting from the periphery thereof toward the wall 128 and at the ends of which are pivotally mounted as is indicated at 137 centrifugally actuated weights 138. The weights 138 are formed in the shape of levers, one of the ends of each lever being adapted to move outwardly by centrifugal force resulting from rotation of the shaft 18 into engagement with the inner surface of the arms 135. The opposite end of each lever is pivotally mounted at 139 in openings formed in the periphery of the ring 132. It will be apparent that the outward movement of the weights 138 resulting from the rotation of the shaft 18 will move the ring 132 against the compression of the spring 133, thus permitting the contact member 123 to engage the contact 126 with the contact 128. The spring 133 is constructed and arranged in such manner that the contact 126 will so close upon the contact 128 when the motor 13 has reached a predetermined operating speed which preferably is just below the normal operating speed of the motor 13. Just below such predetermined operating speed it will be apparent that the spring 133 will move the ring 132 and the contact member 123 in such manner as to open the circuit through contacts 126 and 128 and to close the circuit between contacts 126 and 127.

Contact 128 is connected to one side 141 of a power line 142 in series with the solenoid 119 of the solenoid actuated valve 121 by conductors indicated at 143. Contact 127 also is connected to the same side 141 of the line 142 by conductors 144. Contacts 126 and the running winding 146 of the motor 13 are connected to the other side 147 of the line 142 by conductors 148 and 149 respectively. The running winding 146 also is connected to the side 141 of the line in parallel with starting winding 124 by one of the conductors 144. When switch 151 controlling the line 142 is closed prior to the starting of the motor 13, it will be apparent that an electrical circuit will be made through contacts 126 and 127 for energizing the starting winding 124 of the motor 13. Thereafter the motor will start and will accelerate un-

til such time as the motor shaft 18 has reached the predetermined speed previously referred to in which event the operation of the centrifugally actuated switch 122 will close the circuit through the contacts 126 and 128 thereby opening the circuit through the starting winding 124 and closing the circuit through the solenoid 119 of the solenoid actuated valve 121.

It will also be apparent that upon closing the switch 151 controlling the line 142, that the starting of the motor 13 will result in driving the air pump 46, the fuel pump 47, and the fuel metering pump 48 at the speed of the motor shaft. However, due to the fact that the solenoid actuated valve 121 is not at such time energized in such manner as to open the conduit 111 beyond the needle valve 116, fluid pressure in the discharge port 104, in the pressure chamber 102, the discharge passage 109 and the discharge conduit 111 will tend to increase between the metering pump 48 and the solenoid actuated valve 121. Since the rotor 89 of the metering pump 48 is exposed to the fluid pressure within the pressure chamber 102 and the discharge passage 104, it will be apparent that the rotor 89 will tend to be forced away from the wall 91 against the compression of the spring 88. Since liquid fuel is relatively non-compressible, it will also be apparent that a considerable increase in fluid pressure in the pressure chamber 102 and the discharge port 104 will occur immediately upon the starting of the motor 13 and the pumps 46, 47, and 48. When the fluid pressure in the pressure chamber 102 and the discharge port 104 has increased to a predetermined value, depending upon the calibration of the spring 88, the rotor 89 will be moved away from the wall 91 a sufficient amount to render the metering pump 48 inoperative for the purpose of pumping measured quantities of fuel from the inlet port 107 to the discharge port 104. Thereafter the fluid pressure in the pressure chamber 102 and the discharge port 104 will be relieved along the wall 91 to the pumping chamber 87 and in such event the fluid pressure in the supply conduit 111 will decrease or in any event will not tend to increase beyond the predetermined fluid pressure previously referred to.

When the motor 13, the pump 46, the pump 47, and the fuel metering pump 48 have all reached predetermined speed just below normal operating speed for all of such units, the centrifugally actuated switch 122 will operate in such manner as to open the circuit between the contacts 126 and 127 and to close the circuit through the contacts 126 and 128 thereby actuating the solenoid actuated valve 121 in such manner as to open the needle valve 117 upon the orifice 115 to permit the flow of fuel through the fuel supply conduit 111. When the solenoid actuated valve 121 is so opened, the pressure in the discharge port 104 and the pressure chamber 102 will be relieved to such an extent as to permit the rotor 89 to be resiliently urged by the spring 88 into operative relation to the wall 91. Thereafter the metering pump 48 will supply measured quantities of fuel from the pumping chamber 87 to the nozzle 28 to be there mixed with air at approximately the same pressure delivered by the air pump 46 to the nozzle 28.

Operation of the ignitor 42 thereupon will ignite the combustible charge formed in the burner nozzle 28 and the burner thereafter will continue to operate under normal operating conditions during the continuation of an operating cycle.

for the oil burner apparatus. When the switch 151 is opened at the end of such normal operating cycle for the oil burner apparatus by operation of the control mechanism 23 the speed of the motor shaft 18 will decrease. When the speed of shaft 18 is decreased to the predetermined operating speed previously referred to, the centrifugally actuated switch 122 will operate to open the circuit between contacts 126 and 128. However, the circuit through switch 151 having already been opened, the solenoid actuated valve 121 will again permit the closing of the needle valve 117 upon the seat 116 immediately upon opening of the circuit through switch 151. The resulting immediate rise in pressure in the supply conduit 111 will increase the fluid pressure in the pressure chamber 102 and the discharge port 104 to such an extent as to render the fuel metering pump 48 inoperative in the manner previously described.

It will be apparent that while air will be supplied to the discharge orifice 29 by the air supply pump 46 during all operating speeds of the air pump 46, fuel will only be supplied to the orifice 29 for mixture with the air so discharged by the orifice 29 above the predetermined operational speed previously referred to for the motor 13, the pump 46, the pump 47, and the fuel metering pump 48.

While I have illustrated and described a preferred embodiment of my invention, it is understood that this is capable of modification, and I therefore do not wish to be limited to the precise details set forth, but desire to avail myself of such changes and alterations as fall within the purview of the following claims.

I claim:

1. An oil burner system comprising a burner nozzle, fuel and air pumping means for supplying fuel and air to said burner nozzle, said fuel pumping means having a discharge port connected with said nozzle, means responsive to the speed of operation of said fuel and air pumping means for increasing the fluid pressure in said discharge port, said speed responsive means being operative for preventing flow of fuel to said nozzle and for increasing said fluid pressure at speeds below a predetermined operational speed for said fuel and air pumping means, and means responsive to a predetermined increase in said fluid pressure in said discharge port for rendering said fuel pumping means inoperative for supplying said fuel to said burner nozzle below said predetermined operational speed for said pumping means, said speed responsive means being operative for relieving the fluid pressure in said discharge port and permitting flow of fuel to said nozzle at speeds of said pumping means above said predetermined operational speed thereof, said air pumping means being operative at speeds below and above said predetermined speed for supplying a stream of secondary air past said nozzle and said nozzle being operative for mixing the fuel and air supplied thereto and discharging the resulting mixture into said secondary air stream.

2. An oil burner system comprising a burner nozzle, fuel and air pumping means for supplying fuel and air to said burner nozzle, said fuel pumping means having a discharge port connected with said nozzle, means responsive to the speed of operation of said fuel and air pumping means for increasing the fluid pressure in said discharge port, said speed responsive means being operative for preventing flow of fuel to said nozzle and for increasing said fluid pressure at

sure at speeds below a predetermined operational speed for said fuel and air pumping means, means responsive to a predetermined increase in said fluid pressure in said discharge port for rendering said fuel pumping means inoperative for supplying said fuel to said burner nozzle below said predetermined speed for said pumping means, and said fuel pumping means having a pressure chamber connected to said discharge port and exposed to said pressure responsive means for increasing the total effective pressure of said fluid upon said pressure responsive means, said speed responsive means being operative for relieving the fluid pressure in said discharge port and pressure chamber and permitting flow of fuel to said nozzle at speeds of said pumping means above said predetermined operational speed thereof, said air pumping means being operative at speeds below and above said predetermined speed for supplying a stream of secondary air past said nozzle and said nozzle being operative for mixing the fuel and air supplied thereto and discharging the resulting mixture into said secondary air stream.

3. An oil burner system comprising a burner nozzle, fuel and air pumping means for supplying fuel and air to said burner nozzle, said fuel pumping means having a discharge port connected with said nozzle, means responsive to the speed of operation of said fuel and air pumping means for increasing the fluid pressure in said discharge port, said speed responsive means being operative for preventing flow of fuel to said nozzle and for increasing said fluid pressure at speeds below a predetermined operational speed for said fuel and air pumping means, and means responsive to a predetermined increase in said fluid pressure in said discharge port for rendering said fuel pumping means inoperative for supplying said fuel to said burner nozzle below said predetermined speed for said pumping means, said speed responsive means having a discharge port connected with said nozzle, means responsive to the speed of operation of said fuel and air pumping means for increasing the fluid pressure in said discharge port, said speed responsive means being operative for preventing flow of fuel to said nozzle and for increasing said fluid pressure at speeds below a predetermined operational speed for said fuel and air pumping means, and means responsive to a predetermined increase in said fluid pressure in said discharge port for rendering said fuel pumping means inoperative for supplying said fuel to said burner nozzle below said predetermined speed for said pumping means, said speed responsive means having an annular pressure chamber surrounding said discharge port and exposed to said pressure responsive means for increasing the total effective pressure of said fluid upon said pressure responsive means, said speed responsive means being operative for relieving the fluid pressure in said discharge port and pressure chamber and permitting flow of fuel to said nozzle at speeds of said pumping means above said predetermined operational speed thereof, said air pumping means being operative at speeds below and above said predetermined speed for supplying a stream of secondary air past said nozzle and said nozzle being operative for mixing the fuel and air supplied thereto and discharging the resulting mixture into said secondary air stream.

4. An oil burner system comprising a burner nozzle, fuel and air pumping means for supplying fuel and air to said burner nozzle, said fuel pumping means having inlet and discharge ports connected with said nozzle, means responsive to the speed of operation of said fuel and air pumping means for increasing the fluid pressure in said discharge port, said speed responsive means being operative for preventing flow of fuel to said nozzle and for increasing said fluid pressure at speeds below a predetermined operational speed for said fuel pumping means, means responsive to a predetermined increase in said fluid pressure in said discharge port for rendering said fuel pumping means inoperative for supplying said fuel to said burner nozzle below said predetermined speed for said pumping means, and said

fuel pumping means having an annular pressure chamber surrounding said inlet and discharge ports and exposed to said pressure responsive means for increasing the total effective pressure of said fluid upon said pressure responsive means, said speed responsive means being operative for relieving the fluid pressure in said discharge port and pressure chamber and permitting flow of fuel to said nozzle at speeds of said pumping means above said predetermined operational speed thereof, said air pumping means being operative at speeds below and above said predetermined speed for supplying a stream of secondary air past said nozzle and said nozzle being operative for mixing the fuel and air supplied thereto and discharging the resulting mixture into said secondary air stream.

5. An oil burner system comprising a burner nozzle, fuel pumping means for supplying said fuel to said burner nozzle, said fuel pumping means having an inlet port and a discharge port connected with said nozzle, means responsive to the speed of operation of said fuel pumping means for increasing the fluid pressure in said discharge port, said speed responsive means being operative for preventing flow of fuel to said nozzle and for increasing said fluid pressure at speeds below a predetermined operational speed for said fuel pumping means, means responsive to a predetermined increase in said fluid pressure in said discharge port for rendering said fuel pumping means inoperative for supplying said fuel to said burner nozzle below said predetermined speed of said pumping means, and said fuel pumping means having an annular pressure chamber surrounding said inlet and discharge ports and exposed to said pressure responsive means for increasing the total effective pressure of said fluid upon said pressure responsive means, said speed responsive means being operative for relieving the fluid pressure in said discharge port and permitting flow of fuel to said nozzle at speeds of said pumping means above said predetermined operational speed thereof.

6. An oil burner system comprising a burner nozzle, fuel pumping means for supplying said fuel to said burner nozzle, said fuel pumping means having a discharge port connected with said nozzle, means responsive to the speed of operation of said fuel pumping means for increasing the fluid pressure in said discharge port, said speed responsive means being operative for preventing flow of fuel to said nozzle and for increasing said fluid pressure at speeds below a predetermined operational speed for said fuel pumping means, means responsive to a predetermined increase in said fluid pressure in said discharge port for rendering said fuel pumping means inoperative for supplying said fuel to said burner nozzle below said predetermined speed of said pumping means, and said fuel pumping means having a pressure chamber surrounding said discharge port and exposed to said pressure responsive means for increasing the total effective pressure of said fluid upon said pressure responsive means, said speed responsive means being operative for relieving the fluid pressure in said discharge port and permitting flow of fuel to said nozzle at speeds of said pumping means above said predetermined operational speed thereof.

7. An oil burner system comprising a burner nozzle operative for discharging a combustible mixture of fuel and air, a pumping unit associated with said burner nozzle and operative for sup-

plying said mixture to said burner nozzle and a secondary air stream past said nozzle into which said mixture is discharged, said pumping unit comprising a pumping chamber having a rotor disposed therein, resilient means for rotating said rotor against a wall of said chamber for pumping the fuel employed in said mixture to said burner nozzle, said wall having a discharge port therein in opposite relation to said rotor, the fluid pressure in said discharge port being opposed to said resilient means, and means responsive to the speed of said resilient means for discontinuing the supply of said fuel to said burner nozzle and for increasing said fluid pressure in said discharge port, said rotor being movable by the fluid pressure in the discharge port against said resilient means away from said wall for relieving said fluid pressure into said pumping chamber below a predetermined speed of operation of said resilient means.

8. An oil burner system comprising a burner nozzle operative for discharging a combustible mixture of fuel and air, a pumping unit associated with said burner nozzle and operative for supplying said mixture to said burner nozzle and a secondary air stream past said nozzle into which said mixture is discharged, said pumping unit comprising a pumping chamber having a rotor disposed therein, resilient means for rotating said rotor against a wall of said chamber for pumping the fuel employed in said mixture to said burner nozzle, said wall having inlet and discharge ports therein in opposite relation to said rotor, means forming an annular pressure chamber surrounding said inlet and said discharge ports, said pressure chamber being in open communication with said discharge port and being formed between said rotor and said wall, the fluid pressure in said discharge port and pressure chambers being opposed to said resilient means, and means responsive to the speed of said resilient means for discontinuing the supply of said fuel to said burner nozzle and for increasing said fluid pressure in said discharge port and said pressure chamber, said rotor being movable by the fluid pressure in the discharge port and pressure chamber against said resilient means away from said wall for relieving said fluid pressure into said pumping chamber below a predetermined speed of operation of said resilient means.

9. An oil burner system comprising a burner nozzle, means for supplying a combustible mixture of fuel and air to said burner nozzle, said fuel supplying means comprising a fuel metering pump having a discharge port, means supporting said pump for movement in response to pressure, said fuel metering pump being movable in response to the pressure of fuel in said discharge port for rendering said pump inoperative to supply fuel to said nozzle, means responsive to the operation of said fuel and air supplying means for increasing the pressure of fuel in said discharge port below a predetermined operating speed for said fuel and air supplying means, and means forming a pressure chamber connected to said discharge port and associated with said fuel metering pump for accelerating the movement of said fuel metering pump in response to said fuel pressure.

10. An oil burner system comprising a burner nozzle, means for supplying a combustible mixture of fuel and air to said burner nozzle, said fuel supplying means comprising a fuel metering pump, means supporting said pump for movement in response to pressure, said fuel metering pump

being movable in response to the pressure of fuel in the discharge side of said pump for rendering said pump inoperative to supply fuel to said nozzle below a predetermined operating speed for said supplying means, and means responsive to the operation of said fuel and air supplying means for increasing said discharge pressure for rendering said pump inoperative below said predetermined operating speed for said fuel and air supplying means.

11. An oil burner system comprising a motor, fuel and air supplying means driven by said motor, a mixing nozzle, conduits connecting said mixing nozzle to said fuel and air supplying means, a centrifugally actuated switch associated with said motor, a solenoid operated valve in said fuel conduit, said switch and said solenoid actuated valve being provided with an electrical circuit for operating said valve to open the same when the circuit through said switch is closed, said centrifugally actuated switch being operative for closing said circuit for actuating said solenoid actuated valve when said motor is operating at a predetermined speed, said solenoid actuated valve being operative to open said fuel supply conduit when said circuit is closed, said air supplying means being operative at speeds below and above said predetermined speed for supplying a stream of secondary air past said nozzle and said nozzle being operative for mixing the fuel and air supplied thereto and discharging the resulting mixture into said secondary air stream.

12. An oil burner system comprising a motor, fuel and air pumping means driven by said motor, a mixing nozzle for said oil burner system, said mixing nozzle being connected to said fuel and air pumping means by fuel and air conduits, a centrifugally actuated switch associated with said motor, a solenoid valve closing said fuel conduit, an electric circuit for said motor, said switch and solenoid actuated valve being connected in said electrical circuit in parallel relation to said motor for operating said valve to open the same when the circuit through said switch is closed, said centrifugally actuated switch being operative for closing said circuit above a predetermined speed of operation of said motor, said solenoid actuated valve being operative for closing said fuel supply conduit when said circuit is opened, and means responsive to the closing of said fuel supply conduit for rendering said fuel pumping means inoperative, said air pumping means being operative at speeds below and above said predetermined speed for supplying a stream of secondary air past said nozzle and said nozzle being operative for mixing the fuel and air supplied thereto and discharging the resulting mixture into said secondary air stream.

13. An oil burner system comprising an oil and air mixing nozzle, an air pump connected with said nozzle for supplying air thereto, an oil pump, means forming a communication between said oil pump and said nozzle for supplying oil thereto, a motor for operating said pumps, a shut-off valve in said communication which prevents flow of oil to said nozzle when the valve is closed, means effective when the motor attains a predetermined speed for opening said valve, means driven with said air and oil pumps and effective above and below said predetermined speed for flowing a stream of secondary air past said nozzle, said nozzle being constructed and arranged to mix the oil and air supplied thereto and to dis-

charge such mixture into said secondary air stream, and means for dissipating the pressure in said communication ahead of said valve when said valve is closed and said motor is operating below said predetermined speed.

14. An oil burner system according to claim 13 wherein said pressure dissipating means comprises a by-pass around said oil pump.

15. An oil burner system according to claim 13 wherein said oil pump comprises two parts biased together which form said pressure dissipating means, said parts being separable in response to fluid pressure in said communication to relieve said pressure when said valve is closed.

16. An oil burner system comprising an oil and air mixing nozzle, an air pump connected with said nozzle for supplying air thereto, an oil pump, means forming a communication between said oil pump and said nozzle for supplying oil thereto, a motor for operating said pumps, a shut-off valve in said communication biased to closed position and which prevents flow of oil to said nozzle when closed, means effective when the motor attains a predetermined speed for opening said valve and which permits said valve to close when the motor decelerates below its normal running speed, means driven with said air and oil pumps and effective above and below said predetermined speed for flowing a stream of secondary air past said nozzle, said nozzle being constructed and arranged to mix the oil and air supplied thereto and to discharge such mixture into said secondary air stream, and means for dissipating the pressure in said communication ahead of said valve when said valve is closed, said shut-off valve being constructed and arranged so that the fluid pressure in said communication does not retard the closing movement thereof.

17. An oil burner system comprising an oil and air mixing nozzle, an air pump connected with said nozzle for supplying air thereto, an oil pump, means forming a communication between said oil pump and said nozzle for supplying oil thereto, an electric motor for operating said pumps, an electric circuit for said motor, a shut-off valve in said communication which prevents flow of oil to said nozzle when the valve is closed, means energized by said motor circuit when the motor attains a predetermined speed for opening said valve and which permits said valve to close when the motor circuit is opened, means driven with said air and oil pumps and effective above and below said predetermined speed for flowing a stream of secondary air past said nozzle, said nozzle being constructed and arranged to mix the oil and air supplied thereto and to discharge such mixture into said secondary air stream, and means for dissipating the pressure in said communication ahead of said valve when said valve is closed.
